COMBINATION CONNECTER PLUG AND SWITCH

Emanuel B. Barnitz, Johnstown, Pa.

Application April 25, 1934, Serial No. 722,376

2 Claims. (Cl. 173—332)

The connecter of the present invention contemplates in its preferred form, a plug of novel construction for use on electrical appliances of of various miscellany, especially irons, the plug 5 including in its construction, a movable cord or cable carrying ferrule usable as a finger piece to facilitate disengagement of the plug from an appliance without exerting pressure on the cord.

The connecter of my invention, while prefer- 10 ably employing a plug of novel construction, may nevertheless be composed of a plug of conventional design in pivotal engagement with a cord or cable carrying ferrule of novel construction which preferably extends from the plug at right 15 angles and is movable about the plug in an arc to relieve stress on the cord during use of the connecter.

A further embodiment of the invention is to provide a connecter which, in its preferred form, 20 embodies a novel form of plug with a movable cord carrying ferrule and a novel form of switch in the plug preferably interposed between the ferrule and the plug contacts.

Other objects of my invention will be apparent 25 from the following description of the present preferred forms thereof, taken in connection with the accompanying drawing, wherein

Fig. 1 is a perspective view of an electric connecter constructed in accordance with the present invention;

Fig. 2 is a side elevational view of the plug portion of the connecter showing one of the sides thereof removed to show the details on the interior of the latter;

Fig. 3 is a horizontal sectional view, taken on the line 3—3 of Fig. 2, looking in the direction of the arrows;

Fig. 4 is a vertical sectional view, taken on the line 4—4 of Fig. 2, looking in the direction of the arrows;

Fig. 5 is a detail fragmentary sectional view through the switch carrying portion of the plug;

Fig. 6 is a detail fragmentary plane view of a modified form of connecter; and

Fig. 7 is a side elevational view of the same, a part thereof being broken away to disclose details.

In its preferred form, the connecter of the present invention consists of a plug, generally designated 8, which is constructed in two parts com- 50 plementarily formed to house details of the invention hereinafter described. Preferably the plug is slightly larger than a plug of conventional design and is provided in one wall thereof, adjacent its upper terminals, with an opening 9 through which one end of a cord or cable carrying

ferrule 10 is pivotally mounted. As shown to advantage in Fig. 3 of the drawing, the ferrule 10 is composed of a head 11 the sides of which are rounded to engage complementary walls of the opening 9, said walls converging slightly toward their outer extremities to prevent withdrawal of the head of the ferrule through the outer wall of the plug. The head 11 issues into a cylindrical body of appreciable length to form a finger piece to serve in a manner more fully hereinafter set forth. The ferrule is hollow throughout its length to receive a cord or cable 12, the bore of the ferrule within the head 11 being divided to provide parallel openings 13, which terminate at the free terminal of the head on opposite sides 16 of an extension 14. The extension 14 projects beyond the head 11 for a distance which is sufficient to span a recess formed in the plug by the opening 9 in one side of the latter, and a semi-circular cavity 15 formed in the opposite side of the plug. As the ferrule 10 is moved laterally the extension 14 wipes over the wall of the cavity 15 and serves as a partition to separate wire strands 16, which extend into the plug from the cord 12 and are engaged with parts on the interior of the plug, as more fully hereinafter set forth. In this way the ferrule 10 is mounted directly in the plug, is freely movable laterally therein, and serves as a finger piece to permit the plug to be removed from an electrical appliance, such as an iron, in a facile manner, without exerting any pressure on the cord 12. Furthermore, there is no strain on the cord 12 during the use of an appliance, such as an iron, since the ferrule permits freedom of movement of the appliance independently of the cord. 35

The side or part of the plug which carries the ferrule 10 is also adapted for the reception of contacts 17 preferably mounted in the lower end of the plug for engagement over the pintles or pins of an appliance. One of the contacts 17 is engaged by one of the wires 16, the latter passing through a groove 18 in the plug part, so as to be countersunk in the latter. The other contact 17 is engaged by one end of a conductor strip 19, shown to advantage in Fig. 4, the opposite end of said strip being adapted for normal engagement with a conductor finger 20. The strip 19 is inherently resilient so as to normally flex against the finger 20 to normally close the electrical circuit through the plug when the latter is engaged with an appliance since the finger 20 is engaged with a binding screw 21 to which the other wire 16 of the cord is engaged. For the purpose of opening the circuit I provide an 55

insulated switch key 22 which, in the drawing, I have shown to consist of a discal body having a lug 23 radiating therefrom to which one end of a spring 24 is anchored. The opposite end of said 5 spring is mounted in a recess formed in the plug. The key 22 may also be provided with a peripheral extension 25 through the medium of which the key can be moved on its axis at the option of the user. When the key is in the position 10 shown in Fig. 2 of the drawing, the lug 23 is interposed between the strip 19 and the finger 20, thereby separating these parts to open the circuit.

In the form of invention shown in Figs. 6 and 15 7 of the drawing, a conventional type of plug 26 is illustrated with which a housing 27 is pivotally engaged. In this form of invention I employ a tapered plug 28, the small end of which is provided with an annulus 29, which is fixedly 20 mounted in a corresponding groove formed in the plug 27. The outer end of the plug is mounted in a complementary opening 30, formed in one end of the housing. The plug is provided 25 with a bore through which wire strands 31 of the electric cord or cable are trained, for engagement with contacts in the plug 28, in a manner well known in the art. The strands 31 are separated by a partition 32, extending through the plug. The cord or cable is engaged with the 30 housing 27 in a manifest manner. The housing 27 is in two parts and since the plug 28 is tapered, it can be engaged only from the inside of the housing part in which the opening 30 is formed. Consequently when the other part of 35 the housing is in place, casual disengagement of the plug is prevented and securing means for the latter is unnecessary. The plug is frictionally engaged with the housing but rotative movement thereof is permitted so as to allow rela-

tive movement of the plug and housing. In this form of invention, the housing extends at right angles to the plug to permit use of the housing as a finger piece for disengaging the plug from an appliance. In view of the plug annulus 29, 5 it will be apparent that when pressure is exerted on the housing to disengage the plug from the appliance, separation of the plug and housing is prevented.

Although I have herein described only two 10 forms of my invention, which experiment has shown to be efficient in operation and inexpensive to manufacture, I am nevertheless aware that various changes may be made in the connector without departing from the scope of the 15 invention, as covered by the claims appended hereto.

What is claimed is:

1. An electric connector for appliances including a plug, having contacts for engagement with an appliance, a cord carrying ferrule pivotally mounted in a wall of the plug, the cord of which is in electrical engagement with the plug contacts, and a lug formed on said ferrule and extending across the plug into engagement with an inner wall of the latter and projecting completely through the opposite wall of the plug to hold the wires of the cord out of contact in the plug under all conditions. 20

2. An electric connector for appliances including a two-part plug, one of the parts of which is provided with an opening intermediate its terminals, a cord carrying ferrule engageable in said opening only from the inside of the plug, said ferrule extending at right angles to the plug 25 to serve as a finger piece for facilitating disengagement of the plug from an appliance. 30

EMANUEL B. BARNITZ.
